Primary Examiner — Wan Laymon(74) *Attorney, Agent, or Firm* — Michael J. Feigin, Esq.; Feigin & Fridman(57) **CLAIM**

The ornamental design for the retainer for sleep apnea, as shown and described.

DESCRIPTION

FIG. 1 is a bottom and side perspective view of the retainer for sleep apnea;

FIG. 2 is a bottom view of the top piece of the retainer for sleep apnea;

FIG. 3 is a front view of the retainer for sleep apnea;

FIG. 4 is a rear view of the retainer for sleep apnea; and, FIG. 5 is a side view of the retainer for sleep apnea, the other side being a mirror image thereof.

The broken lines are included for the purpose of illustrating portions of the retainer for sleep apnea and form no part of the claimed design.

1 Claim, 3 Drawing Sheets---
